(57) **CLAIM**

The ornamental design for a bottle, as shown and described.

DESCRIPTION

FIG. 1 is a front perspective view of a bottle showing the new design;

FIG. 2 is a front view of the bottle shown in FIG. 1;

FIG. 3 is a rear view of the bottle shown in FIG. 1;

FIG. 4 is a right side view of the bottle shown in FIG. 1;

FIG. 5 is a left side view of the bottle shown in FIG. 1;

FIG. 6 is a top view of the bottle shown in FIG. 1; and,

FIG. 7 is a bottom view of the bottle shown in FIG. 1.

The broken lines showing of the interior chamber of the bottle show unclaimed subject matter.

The stippling indicates color contrast.
